UNITED STATES PATENT OFFICE

BENJAMIN SKIDMORE, JR., OF GLENCOE, ILLINOIS, ASSIGNOR TO MINETTE E. SKIDMORE, OF CHICAGO, ILLINOIS

APPARATUS FOR AUTOMATICALLY PRIMING CENTRIFUGAL PUMPS

Application filed August 15, 1927. Serial No. 212,982.

This invention relates to improvements in apparatus for priming centrifugal pumps and is particularly adapted though not necessarily limited in its use with bilge pumps and the like, and one of the objects of the invention is to provide an improved apparatus of this character that will be automatic in action.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

Figure 1 is a view partly in side elevation, partly in section and partly broken away of an apparatus of this character constructed in accordance with the principles of this invention.

Figure 2 is a detail sectional view taken on line 2—2, Figure 1.

Figure 3 is a detail sectional view taken on line 3—3, Figure 1.

Figure 4 is a detail fragmentary view of a portion of a modified form of the invention.

Referring more particularly to the drawing the numeral 10 designates generally a tank or receiver in which the liquid to be pumped is delivered through a suitable pipe 11.

The tank or receiver is provided with a cover 12 having a manhole opening closed by means of a manhole cover 13.

Arranged within the receiver is a container 14 which may be of any desired size and configuration and is supported by means of legs 15, preferably three in number, so that the container will be spaced near the bottom of the tank 10.

A second container 16 is also arranged within the receiver and is spaced above the container 14. The container 16 is also of any desired size and configuration and is supported by means of uprights or spacing standards 17.

Leading from the container 16 and through the bottom thereof is a pipe 18 which projects for a considerable distance below the bottom

of the container 14 and is shaped at its lower end to form a return bend 19, the end of the bend having communication as at 20 with a suction pipe 21. The suction pipe passes through suitable openings 22—23 respectively in the containers 14 and 16, but which openings are closed to the interior of the respective containers. The upper end of the suction pipe 21 passes through the manhole cover 13 and is supported thereby by means of a suitable flange 24. The end of the suction pipe has communication with a centrifugal pump 25, the latter being provided with an air valve 26. The lower end 27 of the suction pipe 21 terminates adjacent the bottom of the tank of the receiver 10 and is provided with a valve 28 which opens to permit the liquid to enter the pipe and will close to prevent the passage of the liquid out of the lower end thereof.

Leading from the container 16 preferably through the top thereof is another pipe 29 which also has communication with the lower container 14 through the top thereof and through which pipe air in the container 16 will be forced therefrom and into the container 14 to escape from the latter through a pipe 30 to the receiver or tank 10, a strainer 31 being preferably provided over the end of the pipe 30 and which end 32 is located adjacent and at any desired point above the top of the container 16.

An outwardly opening valve 33 is provided in the container 14 adjacent the bottom thereof and through which valve liquid in the container 14 will be discharged into the tank or receiver 10 under certain conditions.

The pump 25 is operated by a suitable motor 34 and the operation of the motor is controlled by a suitable switch 35.

The switch may be of any ordinary and well known type embodying a control arm 36 which is adapted to be actuated by means of collars 37—38 on a rod 39 that extends through a suitable guide 40 into the tank or receiver 10 and terminates adjacent the bottom of the latter. A float 41 operates upon the rod 39 and the position of the float is controlled by the height of the liquid in the tank or receiver. A shoulder 42 is arranged

adjacent the bottom of the rod 39 to be engaged by the float 41 when the liquid in the tank or receiver is at the lowest level and by engaging the collar 42 the rod 39 will be shifted so as to actuate the control arm 36 to stop the motor 34.

Likewise, when the float 41 engages another shoulder 43 on the rod 39 adjacent the upper end thereof the control arm 36 will be again shifted to start the motor.

The operation of this improved device is as follows. The liquid runs into the tank or receiver 10 through the pipe 11 and as it gradually accumulates and rises in the receiver it will also rise in the suction pipe 21 (the valve 28 opening to permit the liquid to enter the pipe), through the pipe 18 and hollow container 16 to the same level as in the tank or receiver 10, as any air in the suction pipe 21 escapes through the pump 25 and the valve 26. The valve 26 is preferably of the type which opens to the passage of air and to the passage of liquid. Air in the pipe 18 and container 16 will pass to the atmosphere through the pipe 29, container 14 and pipe 30.

When the liquid has reached a predetermined level, preferably even with the upper part of the container 16 or slightly thereabove, it will overflow into the pipe 30, through the strainer 31 and into the container 14. Liquid cannot enter the container 14 through the check valve 33 as it opens outwardly.

As liquid rises in the container 14 air above the surface of the liquid is trapped and will be forced through the pipe 29 into the container 16 above the surface of the liquid therein, thus causing a pressure there equal to the static head of the liquid contained in the pipe 30. Pipes 21 and 18 will then form an inverted siphon as the check valve 28 remains closed.

The added pressure in the container 16 will unbalance the siphon thereby causing the liquid to rise in the pipe 21 and prime the pump 25.

As the liquid rises in the tank or receiver 10 to the predetermined level, float 41 will actuate the switch control member 36, causing the motor 34 to actuate the pump 25.

When the pump has removed the liquid from the tank or receiver 10 to a predetermined low level the float 41 will again actuate the switch to stop the motor.

When the level of the liquid in the tank or container 10 falls below the container 14 all of the liquid will have run out of the container 14 through the check valve 33.

When the liquid again rises in the tank or container 10 this cycle is repeated automatically.

The pipe 18 at its lower end is in the form of a return bend 19 so as to prevent air being drawn into the suction pipe 21.

In Figure 4 there is shown a modified form

of the invention and in lieu of the pipe 18 and the return bend 19 there is provided a valve chamber 44 which has communication through a pipe 45 with the bottom of the container 16 and also by means of a pipe 46 directly with the suction pipe 21. Within the chamber 44 is a float valve 47 which opens when liquid fills the valve chamber and closes when liquid is withdrawn, thus preventing air from being drawn into the suction pipe 21.

The pressure which is exerted above the liquid in the container 16 will force the liquid from the container 16 directly into the pipe 21.

While the preferred forms of the invention have been herein shown and described, it is to be understood that various changes may be made in the details of construction and in the combination and arrangement of the several parts, within the scope of the claims, without departing from the spirit of this invention.

What is claimed as new is:—

1. An apparatus for priming pumps embodying a receiver for liquid, a pump, a suction pipe connected with the inlet of the pump and extending into the receiver, means for compressing air, and means whereby when the liquid reaches a predetermined height in the said receiver air will be compressed and liquid will be forced by the said compressed air into the suction pipe causing priming of the pump.

2. An apparatus for priming pumps embodying a receiver for liquid, a pump, a suction pipe extending from the pump into the receiver, means whereby liquid will be forced into the suction pipe by the action of compressed gas, and means whereby the static head of liquid contained in the receiver from which the liquid is pumped will compress the said gas.

3. An apparatus for priming pumps embodying a receiver for liquid, a pump, a suction pipe extending from the pump into the receiver, an inverted siphon, and means for unbalancing the liquid in said siphon by action of compressed air at a predetermined time in the cycle of operation of the apparatus thereby forcing liquid into the said suction pipe to prime the pump.

4. An apparatus for priming pumps embodying a receiver for liquid, a pump, a suction pipe extending from the pump into the receiver, an inverted siphon, and means for unbalancing the liquid in said siphon by action of compressed air at a predetermined time in the cycle of operation of the apparatus thereby forcing liquid into the said suction pipe to prime the pump, the said air being compressed by the static head of liquid in the receiver from which the liquid is pumped.

5. An apparatus for priming pumps embodying a receiver for the liquid to be pumped, a pump, a suction pipe extending from the pump into the receiver, spaced

- superposed closed containers, a pipe leading from the uppermost container adjacent the top thereof and into the top of the lowermost container, a pipe leading from the lowermost container and open to the atmosphere, the open end of the last said pipe being disposed adjacent the high water level in the receiver and out of direct communication with the uppermost container, a pipe leading 5 from the bottom of the uppermost container and having communication directly with the said suction pipe, and a valve in the suction pipe below the point of connection of the last recited pipe thereto.
- 10 6. An apparatus for priming pumps embodying a receiver for the liquid to be pumped, a pump, a suction pipe extending from the pump into the receiver, spaced superposed closed containers, a pipe leading 15 from the uppermost container adjacent the top thereof and into the top of the lowermost container, a pipe leading from the lowermost container and open to the atmosphere, the open end of the last said pipe being disposed 20 adjacent the high water level in the receiver and out of direct communication with the uppermost container, a pipe leading from the bottom of the uppermost container to a point below the lowermost container, the last said 25 pipe having a return bend at the lower end thereof and having communication with the suction pipe above said bend, and a valve in the suction pipe below the last said point of connection.
- 30 7. An apparatus for priming pumps embodying a receiver for the liquid to be pumped, a pump, a suction pipe extending from the pump into the receiver, spaced superposed closed containers, a pipe leading 35 from the uppermost container adjacent the top thereof and into the top of the lowermost container, a pipe leading from the lowermost container and open to the atmosphere, the open end of the last said pipe being disposed 40 adjacent the high water level in the receiver and out of direct communication with the uppermost container, a pipe leading from the bottom of the uppermost container to a point below the lowermost container, the last said 45 pipe having a return bend at the lower end thereof and having communication with the suction pipe above said bend, and a valve in the suction pipe below the last said point of connection.
- 50 8. An apparatus for priming pumps embodying a receiver for the liquid to be pumped, a pump, a suction pipe extending from the pump into the receiver, spaced superposed closed containers, a pipe leading 55 from the uppermost container adjacent the top thereof and into the top of the lowermost container, a pipe leading from the lowermost container and open to the atmosphere, the open end of the last said pipe being disposed 60 adjacent the high water level in the receiver 65 and out of direct communication with the uppermost container, a pipe leading from the bottom of the uppermost container to a point below the lowermost container, the last said pipe having a return bend at the lower end thereof and having communication with the suction pipe above said bend, a valve in the suction pipe below the last said point of connection, an outlet in the bottom of the lowermost container, and an outwardly opening 70 valve for controlling said outlet. 75
- In testimony whereof I have signed my name to this specification, on this 11th day of August, A. D. 1927.
